GRILLE

Robert T. Bogan, Jr., 3620 High St. NE,
Albuquerque, N. Mex. 87107

Original design application Oct. 17, 1968, Ser. No. 14,032,
now Patent No. 216,463, dated Jan. 13, 1970. Divided
and this application June 16, 1969, Ser. No. 18,582

Term of patent 14 years

Int. Cl. D25—01

U.S. Cl. D13—1

FIG. 1.

FIG. 2.

FIG. 1 is a front elevation of a portion of a grille embodying my new design, a rear elevation thereof being the same in appearance but interposed in alternating relation with the front; and

FIG. 2 is a vertical section, taken along line 2—2 of FIG. 1.

This application is a division of my copending application Ser. No. D. 14,032, filed Oct. 17, 1968, now Pat. No. D. 216,463.

I claim:

The ornamental design for a grille, as shown and described.
